UNITED STATES PATENT OFFICE.

CAMILLE CONTAL, OF PARIS, FRANCE.

DRILLING DEVICE.

Application filed October 8, 1920. Serial No. 415,602.

To all whom it may concern:

Be it known that I, CAMILLE CONTAL, a citizen of the Republic of France, residing at Paris, Seine Department, 11th Rue de Milan, in the Republic of France, engineer, have invented certain new and useful Improvements in Drilling Devices, of which the following is a specification.

This invention relates to drilling devices having several speeds, in which the drill spindle is provided with a sliding pinion adapted to engage alternately with a plurality of concentric toothed portions carried by a disk whose shaft is mounted in the frame of the drilling device in such manner as to be moved perpendicularly to the drill spindle for the purpose of coupling and uncoupling the said disk and of changing the position of the pinion according to the speed to be obtained.

This invention relates to improvements in drilling devices of this class and more particularly to an actuating device for the disk whereby the drilling device can be used in a narrow space in which it would be impossible to make a complete revolution of the operating crank. To this effect the crank is made to actuate the said disk by means of a ratchet member whereby the crank is connected with the disk only in one direction and can return backwards without actuating the drill point.

This invention also consists in a special method of disposing the ratchet member whereby the latter can be given a very simple, strong and inexpensive construction together with a minimum size.

The accompanying drawing represents by way of example a drilling device according to this invention.

Fig. 1 is an elevation of the drilling device.

Fig. 2 is an axial section of the main frame the disk and the crank, on a larger scale.

Fig. 3 is a partial elevation of the disk, on the side of the crank the end of the disk shaft being sectioned at a point flush with the handle.

Fig. 4 is a partial axial section of another form of construction showing a modified form of the locking device for holding the disk shaft.

The actuating disk 1 which contains a plurality of rows of apertures 1^a is secured to the shaft 2, for instance by means of a

screw thread 2^a. A crank 3 is loosely rotatable upon a circular portion 4 of the shaft 2 and is held upon the said shaft by means of a shoulder or a head 5 formed for instance by means of a washer 6 which is riveted, screwed or secured by autogenous welding to the end of the shaft. The handle 3 carries a set of notches constituting interior ratchet teeth 7. The portion 4 of the shaft is traversed by an aperture 8 having therein two pawls 9 spread apart by a spring 10 disposed between the same. The said pawls are disposed in such manner that upon turning the said crank in the clockwise direction, the disk 1 will be actuated thereby, but will be no longer actuated when the crank is turned in the opposite direction.

In case the drilling device is used in a place where there is sufficient room to make a complete revolution, the crank 3 is secured to the disk 1 for instance by means of the screw 11 for the purpose of obtaining a continuous rotary movement. It is of course understood that any other suitable means can be employed for securing the crank to the disk.

The shaft 2 carries at the other end a groove 12 having engaging therein the locking pin 13 under the action of the spring 14. The said pin is slidable in a recess 15 in the frame 19 of the device in such manner that only the outer end of the pin shall be visible. The said pin is provided with an aperture 13^a through which the shaft 2 is caused to pass freely when the locking pin has been driven inwardly.

At 20 is a washer of larger size than the aperture 13^a which serves to limit the stroke of the shaft 2 when the latter is moved, the washer contacting the locking pin 13. This washer is held in fixed position upon the shaft 2 by means of a screw 21. To change the speed, the locking pin is pushed inwardly, and this permits of the lateral movement of the disk 1, whereby the pinion 16 is enabled to pass from one set of apertures 1^a to another set.

Figure 4 shows that the groove 12 can be disposed at any suitable point instead of at the end of the shaft 2, for instance in line with the longitudinal shaft 17 of the drill spindle. In this case the locking pin 13 is disposed perpendicularly to the direction of the said shaft 17 within a hollow boss 18 disposed on one side of the frame 19. This locking pin is provided with a head 13^b.

whereby it can be drawn outwardly to disengage the groove 12.

Claims:-

1. In a drill, the combination of a socket member, a shank secured to the socket member, a tool spindle having one end journaled in the socket member with its axis in alinement with the shank, a pinion mounted slidably upon the tool spindle and held from rotation thereon independently thereof, a disk-shaped gear having an axle journaled in the socket member perpendicularly to the axis of the shank and spindle and movable laterally from said axis, said gear member having a plurality of circular series of holes adapted to mesh respectively with the teeth of the pinion, and means carried by the socket member serving to hold the gear disk in normal position meshing with the pinion and holding the pinion from endwise movement on its spindle.
2. In a drill, the combination of a shank, a socket member carried by the lower end of the shank, said socket member having a lateral and a bottom bearing socket having their axes at right angles to each other, a bracket secured to the socket member and projecting downwardly terminating in a bearing hub having a bore in alinement with the bottom socket of the socket member, a tool spindle journaled in the hub and having its upper end journaled in said bottom socket, a pinion mounted upon the spindle between the socket member and the hub and adapted to slide along the same but held from rotation thereon independently of the spindle, a gear wheel supported for rotation in the other socket of the socket member and having a plurality of circular series of holes adapted to mesh with the teeth of the pinion in any position of adjustment of the pinion along the spindle, and means to hold the gear wheel from moving laterally out of engagement with the pinion, said last mentioned means including a transverse shaft adapted to slide lengthwise and carrying the said gear wheel and having a circular groove therein, and locking means disposed upon the socket member and engaging said groove.

3. In a drill the combination of a shank, a socket member carried by the lower end of this shank, the socket member being provided with a lateral bearing and a step bearing whose axes are at right angle, an arm extending from the socket member and ending into a bearing the opening of which is in line with the step bearing of the socket member, a drill-carrying shaft located in said bearing and in the step bearing, a pinion mounted on the drill-carrying shaft between the socket member and said step bearing and adapted to slide on the said shaft, a gear wheel revolving on the lateral bearing and comprising several circular rows of holes adapted to mesh with the teeth of the pinion in the determined positions which the pinion may occupy, means for preventing the gear wheel from moving laterally and from coming out of mesh with the pinion, said means being constituted by a transverse shaft adapted to slide lengthwise and carrying the gear wheel and in which is provided a circular groove, a spring latch sliding in the socket member, this latch or lock having an opening through which the said shaft can pass freely and adapted to enter into said groove for the purpose of maintaining the gear wheel in a normal position with reference to the shaft.

4. In a drill, the combination of a disk having a plurality of concentric series of holes formed in one side thereof, supporting means for the disk permitting lateral movement thereof, a pinion having a series of round-ended teeth adapted to enter and mesh with the several series of holes and whereby the pinion is held from endwise movement, a spindle on which said pinion is journaled and means serving to normally prevent the lateral movement of the disk and disengagement from the pinion.

In testimony, that I claim the foregoing as my invention I have signed my name in presence of two subscribing witnesses.

CAMILLE CONTAL.
